UNITED STATES PATENT OFFICE

154,324

DESIGN FOR A TOE NAIL POLISHING DEVICE

Patricia Reid, Chicago, Ill.

Application February 17, 1948, Serial No. 144,531

Term of patent 14 years

(Cl. D86—10)

To all whom it may concern:

Be it known that I, Patricia Reid, a citizen of the United States residing in Chicago, in the county of Cook and State of Illinois, have invented a new, original, and ornamental Design for a Toe Nail Polishing Device, of which the following is a specification, reference being had to the accompanying drawing, forming a part thereof.

I claim:

The ornamental design for a toe nail polishing device, as shown.

PATRICIA REID.
